CLOWN HEAD FOR PLAYGROUND APPARATUS

Robert S. Wormser, Hillsdale, Mich., assignor to Game-Time, Inc., Litchfield, Mich., a corporation of Michigan

Filed Apr. 1, 1968, Ser. No. 11,243

Term of patent 14 years

U.S. Cl. D34—4

Int. Cl. D21—04

FIG. 1 is a side elevational view of a clown head for playground apparatus in accord with my new design, the opposite side being identical,

FIG. 2 is a front elevational view,

FIG. 3 is a top plan view, and

FIG. 4 is a bottom view.

The broken lines in FIG. 1 indicating a playground cannon and shown fragmentarily in FIGS. 3 and 4 are for illustrative purposes only.

I claim:

The ornamental design for a clown head for playground apparatus, substantially as shown and described.
